Inventor:

Jaroslav Skorkovsky

UNITED STATES PATENT OFFICE.

JAROSLAV SKORKOVSKÝ, OF HRADEC KRALOVE, CZECHOSLOVAKIA.

APPARATUS FOR MANUFACTURE OF CONCRETE TUBES.

Application filed October 27, 1920. Serial No. 420,052.

To all whom it may concern:

Be it known that I, JAROSLAV SKORKOVSKÝ, a citizen of the Czech-Slovak Republic, residing at Hradec Kralove, Czechoslovakia, have invented certain new and useful Improvements in Apparatus for Manufacture of Concrete Tubes (for which I have made application for patents as follows, Czecho-Slovakia October 18, 1919, and Germany Oct. 28, 1919), of which the following is a specification.

My invention refers to reinforced concrete tubes and beams, and more especially to a device for manufacturing such tubes and beams.

Hitherto it was possible to produce only tubes of reinforced concrete of circular or ovoid cross-section which were provided with an annular iron reinforcement. Where longitudinal reinforcing members were employed, the longitudinal rods only served for stiffening and distributing purpose without being required to receive the inner stresses arising in consequence of axial bending.

Such tubes as above have been manufactured in vertical moulds that could be taken asunder and which only allowed of making pieces of limited length, the tubes consequently being employed merely for purposes of sewerage and the like, any other use being impossible owing to the tubes lacking a suitable longitudinal reinforcement and having only a limited length.

The manner in which the transverse reinforcement was formed, has been perfected by various arrangements, but there always remained the necessity of ramming the concrete, such ramming either taking place by manual labour or by simply pressing a screw thread through the concrete material, this latter method although being quicker, than manual labour, nevertheless being unfit for achieving a correct compression of the concrete or a reliable setting of the concrete around the iron.

My invention renders it possible to produce by machinery tubes or beams of reinforced concrete of any desired shape and length in an extremely economical manner without employing special moulds, the tubes or beams being provided with longitudinal and transverse reinforcements corresponding to the inner stresses, so that they can not only be employed as tubes for sewerage and water conduit piping, which are sub-

ject only to radial pressure or tensile strains, but also as structural elements of any kind (such as beams, poles, pillars and the like) required to be capable of withstanding bending stresses.

Hitherto it has been necessary to produce such constructions provided with a longitudinal reinforcement and intended to serve as beams, poles, pillars and the like, by manual labour, and this either in an expensive and complicated mould or in expensive metal moulds adapted to be taken to pieces, the reinforcement constructed in advance, being inserted in the moulds, after which the ramming of the concrete by hand was commenced, a considerable loss of time ensuing from this method which was moreover very imperfect, in consideration of the complicity of the iron skeleton inserted forming an obstacle in the way of correct ramming. The finished concrete bodies could not be removed from the moulds until the material had set.

In the drawings attached to this specification and forming part thereof, a machine for carrying my invention into practice is illustrated by way of example. In the drawings

Fig. 1 is a longitudinal section,

85

Fig. 2 is a side view and

Fig. 3 is a plan of the machine.

Fig. 4 is a detail.

Referring to the drawings, the concrete is fed to the charging funnel 1 which may be provided with a conveyor worm, and proceeds from the latter to a casing 2 containing a conveyor worm 3 which moves the concrete further and compresses it. The conveyor worm is elongated to form a mandrel 4, 5 which determines the size of the hollow interior of the body to be produced.

The concrete material is forced into the intermediate space formed between the core mandrel 5 and the mouth piece 6 of the press by the worm 3.

The outer surface of the casing 2 is provided with longitudinal grooves 7 in which the iron wires or rods 8 are inserted before commencing to press the concrete, the insertion of the said wires being effected in such a manner that the ends of the rods project a little beyond the edge of the casing 2.

In order to ensure the reinforcement being drawn along by the concrete material in the beginning, before both of them arrive in the opening of the mouth piece reduced in

size by the full diameter of the mandrel, a frame 21 of wood or sheet metal which fits into the cavity of the mouth piece, is employed, the holes contained in this said frame 5 being slipped over the ends of the longitudinal reinforcements and the frame itself then being attached to the wires by means of nuts or in some other suitable way.

Simultaneously the projecting ends of 10 these wires or rods 8 are fastened together with the beginning of the spiral reinforcement 9 which is fed in from the outside through an aperture 10 by means of a helical groove provided in the interior of the cylinder 12, which conducts the said wire to the mouth of the casing 2 where it is wound around the wire 8. The wire 9 fed in is 15 unwound from the drum 11 which is supported in bearings on the cylinder 12 in such a manner as to be freely rotatable, and which responds to the movement caused by the unwinding of the wire, so that in this manner only just sufficient wire is unwound 20 as is required for the helical winding on the 25 straight wires 8.

The wire 9 is taken over a chute 13 or a roller attached to an arm 14, in order to facilitate the entrance of the wire 9 into the cylinder 2, the arm 14 being screwed firmly 30 into the cylinder 12.

The cylinder 12 has a rotary motion produced by the toothed wheel 15 which is keyed onto the cylinder 12 being rotated simultaneously with the conveyor worm 3. 35 The toothed wheel 15 as well as the toothed wheel 16 which is keyed on to the shaft of the worm, engage with corresponding toothed wheels of the back gear shaft, the axis of which may be arranged in parallel 40 with the axis of the worm in such a manner that the wheel 16 is made to engage directly with the wheel 17 of the back gear and indirectly, under interposition of the wheel 18, with the wheel 19 of the back gear, all 45 this for the purpose of achieving a rotation on the part of the cylinder 12, which is contrary to the rotation of the worm 3. The rotation of the cylinder 12 also results in a rotation of the arm 14 with the chute 13, 50 the wire 9 thus being wound around the wires or rods 8. In the place where the windings of the worm 3 cease and where its axis passes into the mandrel, the space through which the concrete material is 55 moved forward, is enlarged.

This space contains helical vanes 20 fitted at the head end of the cylinder 12 (Figs. 1 and 4); owing to these guide vanes rotating in the opposite direction to that of the 60 worm, and moreover owing to their being arranged in the vicinity of the inner circumference of the mouth piece, the concrete is pressed straight into the cavity of the mouth-piece over the whole of its cross-section, thus achieving a reliable envelopment 65

of the iron reinforcement by the concrete and simultaneously counteracting the twisting of the concrete as well as of the iron reinforcement carried along by the material.

When the concrete is forced into the cavity of the mouth piece by the rotation of the worm 3 and of the vanes 20, the concrete presses against the frame 21 which is connected with the wire reinforcement (Fig. 4), and carries the said frame forward, together 70 with the reinforcement in continuing its own forward motion. As soon as the concrete then reaches the space, the cross-section of which is reduced by the full cross-section of the mandrel, the reinforcement is 75 also pressed into the concrete with such a force, owing to the powerful compression of the concrete, that the further carrying along of the straight wires lying loosely in the longitudinal grooves, as well as the spiral reinforcement which takes place automatically, 80 is now continued undisturbedly solely on the basis of the adhesion between the concrete and the iron.

It results therefrom that the concrete 85 pressed into the mouth piece by the conveyor worm progresses continuously with the formation of the reinforcement 8, 9; the initial movement of the straight wires and of the spiral reinforcement rigidly connected therewith, being called forth by means of a frame 21 rigidly connected with the longitudinal reinforcement, whilst the further forward movement of the two reinforcements is ensured in consequence of their being pressed tightly against one another owing to the firm compression of the concrete.

I claim:

1. In a device of the kind described in combination a conveyor worm, a casing surrounding said conveyor worm, a mouth piece of substantially annular section connected with said casing, grooves in the walls of said conveyor worm, for guiding reinforcing wires in parallel with the worm axis and means for winding a wire spirally around said reinforcing wires before their entering said mouth piece.

2. In a device of the kind described in combination a conveyor worm, a casing surrounding said conveyor worm, a mouth piece of substantially annular section connected with said casing, grooves in the walls of said conveyor worm for guiding reinforcing wires in parallel with the worm axis, a cylinder adapted to rotate coaxially with, but in a direction opposite to that of said worm, an arm extending from said cylinder and means for causing a wire guided by said arm to be wound spirally around said reinforcing wires before their entering said mouth piece.

3. In a device of the kind described in combination a conveyor worm, a casing sur-

rounding said conveyor worm, a mouth piece of substantially annular section connected with said casing, grooves in the walls of said conveyor worm for guiding reinforcing wires in parallel with the worm axis, a cylinder adapted to rotate coaxially with, but in a direction opposite to that of said worm, helical vanes on the free end of said cylinder, an arm extending from said cylinder 10 extending into said mouth piece and means for causing a wire guided by said arm to be wound spirally around said reinforcing wires before their entering said mouth piece. 4. In a device of the kind described in combination a stationary casing, means for feeding plastic material into said casing, a worm adapted to rotate within said casing, 15 a movable cylinder adapted to rotate on and around said stationary casing in a direction opposite to the direction of rotation of said worm, a mouth piece on said stationary casing, a mandrel forming a continuation of said worm and extending into said mouth-piece, grooves in said stationary casing for guiding straight wires extending into said mouth piece and means on said rotary cylinder for causing a wire to be wound spirally around said straight wires before their entering said mouth piece.

In testimony whereof I affix my signature. 30
JAROSLAV SKORKOVSKÝ.
